UNITED STATES PATENT OFFICE

HIRSCH RAKOWITZKY, OF VIENNA, AUSTRIA, ASSIGNOR TO WESTMINSTER SECURITIES LIMITED, OF LONDON, ENGLAND, A BRITISH COMPANY

COIN TESTER FOR AUTOMATIC VENDING MACHINES AND THE LIKE

Application filed April 4, 1929, Serial No. 352,535, and in Austria March 24, 1928.

The present invention is for improvements in or relating to coin testers for automatic vending machines and the like, and has for one of its objects to provide a simple and efficient device for detecting smooth spurious discs.

A coin tester for automatic vending machines has already been proposed for determining whether the disc introduced has portions in relief or is smooth. If a smooth disc is introduced instead of a genuine coin, it is prevented by the coin tester from passing into the automatic machine. This is effected by the disc striking a spring which projects it between two teeth arranged opposite to each other and resiliently pressed towards each other. A stamped or minted coin will be gripped by the teeth, whereas a smooth disc will slip through them. This proposed coin tester, however, is apt to be unreliable and is very complicated.

According to the primary feature of the present invention, the teeth are so arranged as to maintain a minted coin suspended, with the raised rim of the coin gripped between the teeth, while the coin swings in its own plane about the teeth, and, because of such swinging movement, becomes disengaged from the teeth and passes into the automatic machine, but said teeth permit a smooth disc, without a raised rim, to pass straight through between them.

Thus the coin tester according to the present invention avoids a reversed movement of the coin such as is caused in the aforesaid prior proposal, and, instead, the coin is merely deflected sideways from its straight path.

Other features of the invention will be described hereinafter with reference to the accompanying drawings, which show, by way of example, a construction of a coin tester according to the invention.

45 In these drawings:

Figure 1 is a front elevation,

Figure 2 is a side elevation,

Figure 3 is a section on line A—B of Figure 1, and

50 Figure 4 is a detail view.

Like reference characters indicate like parts throughout the drawings.

A strip 1 formed with a coin chute *k* has a cover strip 2 so that the chute *k* is closed. At their lower ends both strips 1, 2 are cut away at 3, and to the outside of each strip plates 4 and 5 are secured by means of countersunk screws. On these plates there are pivoted by means of pins 6, 7 (Figures 2 and 4), arms 8, 9 having teeth 10, 11 which reach into the gaps 3 at the lower ends of the strips 12. The gaps 3 are illustrated as being so arranged that the teeth 10, 11 are located towards one side of the chute *k*. The plates 4, 5 also carry, in mountings 12, 13 springs 14, 15 which press against the arms 8, 9 so that the points of the teeth 10, 11 are normally in contact with one another. The tension of the springs 14, 15 may be regulated by means of set screws 8. The lower ends of the strips 1, 2 are cut back in bevelled formation at *r* at one side of the gaps 3, for a purpose to be hereinafter indicated.

In Figure 1 a minted coin 18 (viz a coin with a raised or upset rim and with portions of its faces in relief) is shown in two positions. The raised or upset rim is indicated in the drawing by the double line. A smooth disc 19 without such a rim is shown in the conduit 20 which is for "rejects" and which may return the disc to the outside of the machine; the conduit 21 conveys the coins 18 into the automatic machine.

If a correctly minted coin 18 is introduced into the coin chute *k* it will be gripped between the teeth 10, 11 and, because of its raised rim, will be suspended and will swing in its own plane about the points of the teeth (see the second position shown in Figure 1) until it strikes the bevelled edge or stop face *r*. Owing to the impact, it will be disengaged from the points of the teeth and will drop into the conduit 21.

A smooth disc 19, however, will slide between the teeth 10, 11 without being caught or gripped by them, and will drop into the "reject" conduit 20. It will be seen that the teeth 10, 11 are designed in such a manner that a tapered space (Figure 3) is left between them transversely of the direction in

which the coin falls. During its passage past the teeth, the disc 19 bears with its edge against the tapered faces of the teeth 10, 11, and these faces tend to deflect the disc to the left (as seen in Figure 3) and thus direct the disc into the "reject" conduit 20.

It is preferable to arrange the coin chute *k* not vertically, but inclined as indicated by broken lines in Figure 1, in order that the 10 coins may roll along that side of the chute *k* which is the nearer to the teeth 10, 11.

I claim:—

1. A coin tester for vending machines and the like for determining whether a coin is 15 minted comprising two opposed teeth between which the coin is arranged to slide, said teeth being tapered to one side, means whereby said teeth are resiliently pressed towards each other, the teeth being arranged to maintain a minted coin suspended with the raised rim of the coin gripped between the teeth, a coin chute having a shoulder at its lower end to one side of the opposed teeth, the parts being so constructed that the coin when held 25 suspended by the teeth will swing in its own plane about the teeth and strike the shoulder of the chute thereby releasing the coin from the teeth and permitting the coin to pass into the machine while a smooth disc without a 30 raised rim will pass straight through between the teeth.

2. A coin tester for vending machines and the like for determining whether a coin is minted, comprising two opposed knife edges 35 between which the coin is arranged to slide, said edges being tapered to one side, means whereby said edges are resiliently pressed towards each other, the edges being arranged to maintain a minted coin suspended with the raised rim of the coin gripped between the knife edges and to permit the coin to swing 40 in its own plane, a coin chute, means associated with the knife edges for engaging the coin when held suspended by the knife edges 45 and when swung in its own plane about the knife edges thereby releasing the coin from the knife edges and permitting the coin to pass into the machine while a smooth disc without a raised rim will pass straight 50 through between the knife edges.

3. A coin tester for vending machines and the like for determining whether a coin is minted comprising two opposed teeth between 55 which the coin is arranged to slide, said teeth being tapered to one side, means whereby said teeth are resiliently pressed towards each other, and a stop abutment in adjacent location to the teeth, which teeth are so arranged as to retain a minted coin suspended with the raised rim of the coin gripped between the teeth, the parts being so constructed that the 60 coin when held suspended by the teeth will swing in its own plane about the teeth and strike the stop abutment, thereby releasing 65 the coin from the teeth and permitting the

coin to pass into the machine while a smooth disc without a raised rim will pass straight through between the teeth.

4. A coin tester for vending machines and the like for determining whether a coin is 70 minted comprising two opposed teeth between which the coin is arranged to slide, said teeth being tapered to one side, a coin chute, means for resiliently pressing said teeth together, which teeth are so arranged in the 75 chute as to maintain a minted coin suspended with the raised rim of the coin gripped between the teeth laterally of the center of the coin, thereby permitting the coin to swing in its own plane, and means associated with the 80 teeth for disengaging the coin therefrom when held suspended by the teeth and swung in its own plane about the teeth thereby releasing the coin from the teeth and permitting the coin to pass into the machine while a 85 smooth disc without a raised rim will pass straight through between the teeth.

5. A coin tester for vending machines and the like for determining whether a coin is 90 minted comprising two opposed teeth between which the coin is arranged to slide, means for resiliently pressing the teeth toward each other, the teeth being arranged to maintain a minted coin suspended with the raised rim of the coin gripped between the teeth, and to 95 permit the coin to swing in its own plane, means associated with the teeth for disengaging a coin therefrom when held suspended by the teeth and swung in its own plane about the teeth thereby releasing the coin from the teeth and permitting the coin to pass into the machine, said teeth forming between them 100 a tapered space transversely of the direction in which the coin falls through the chute in order to deflect a smooth disc.

6. A coin tester for vending machines and the like for determining whether a coin is minted comprising an intake coin chute, opposed teeth between which the coin is arranged to slide, means for resiliently pressing 110 said teeth towards each other, a chute leading to the machine and a return conduit, which teeth are so arranged in relation to the intake chute and the one leading to the machine as to maintain a minted coin suspended with 115 the raised rim of the coin gripped between the teeth, a shoulder so associated with the teeth that the coin when held suspended by the teeth will swing in its own plane about the teeth and strike the shoulder thereby releasing the coin from the teeth and permitting the coin to pass into the machine, said teeth being arranged to form between them 120 a tapered space transversely of the direction in which the coin falls from the intake chute 125 in order to direct a smooth disc into the return conduit.

In testimony whereof I affix my signature.
